UNITED STATES PATENT OFFICE.

JESSE P. MILLER, OF LEWIS, LOUISIANA.

SAFETY APPARATUS FOR OIL-TANKS.

1,059,191.

Specification of Letters Patent. Patented Apr. 15, 1913.

Application filed July 13, 1912. Serial No. 709,301.

To all whom it may concern:

Be it known that I, JESSE P. MILLER, a citizen of the United States, residing at Lewis, in the parish of Caddo and State of Louisiana, have invented new and useful Improvements in Safety Apparatus for Oil-Tanks, of which the following is a specification.

An object of the invention is to provide an apparatus for preventing explosions of oil tanks or the burning of the oil contained in the tanks.

The invention embodies, among other features, a device embodying a valve normally mounted in open position in the vent pipe of an oil tank, said valve having connection with a fusible member which, when fused, will release the valve and permit the same to gravitate into closed position to close the vent pipe.

In the further disclosure of the invention reference is to be had to the accompanying drawings constituting a part of this specification, in which similar characters of reference denote corresponding parts in all the views, and in which:

Figure 1 is a fragmentary vertical sectional view of an oil tank, showing my apparatus applied to the vent pipe thereof, the valve being shown in normal position; Fig. 2 is a horizontal sectional view taken on the line 2—2 in Fig. 1, the valve being shown in closed position and in section; and Fig. 3 is a horizontal sectional view taken on the line 3—3 in Fig. 1.

Referring more particularly to the views, I disclose a tank 10 having a vent pipe 11 mounted to extend upwardly from the top of the tank, a suitable inlet pipe 12 being connected with the tank 10 for the purpose of supplying oil thereto. Mounted to swing in the vent pipe 11 is a valve 13, normally arranged in a vertical position and preferably weighted on the under outer end thereof so that the valve, when released, will gravitate into closed position, a lug 14 being projected from the inner face of the vent pipe 11 and adapted to form a seat for the free end of the valve 13 to support the same in closed position.

Uprights 15 are secured to the upper end of the vent pipe 11, one of the said uprights terminating in an eye 16 having one end of a fusible member 17 secured thereto, a chain 55 or cord 18 being connected to the other end of the fusible member and adapted to pass

over a pulley 19 journaled on the upper end of the other upright 15, the said chain being adapted to pass through a restricted opening 20 formed in a wall of the vent pipe 11 and having connection with the free end of the valve 13 to normally retain the valve in open position.

A reticulated burner plate 21 is secured in the vent pipe 11 above the valve 13 and it will be readily seen that if, through a bolt of lightning or other means, the gases which exhaust through the vent pipe 11 from the oil tank 10, are ignited the same will burn above the reticulated burner plate 21 and it will be further seen that the heat produced by the combustion of the mentioned gases will fuse the member 17 and thus release the chain 18 and also release the valve 13 from normal position, thus causing the valve to 75 gravitate into closed position to inclose the vent pipe 11, thus preventing the flame from entering the tank 10 and attacking the oil contained therein.

Having thus described my invention, I claim:

1. In a device of the class described, the combination with a vent pipe for connection with a tank, of a valve mounted to swing in the said vent pipe and gravitationally movable into closed position, a lug projected from a wall of the vent pipe and forming a seat for the free end of the said valve, a reticulated burner plate mounted in the said vent pipe over the said valve, uprights extended upwardly from the said vent pipe, a fusible member secured to one of the said uprights, a pulley journaled on the other upright, and a chain connected to the said valve and extending over the said pulley to connect with the said fusible member to normally retain the said valve in open position.

2. In a device of the class described, the combination with a vent pipe for connection with a tank, of a valve gravitationally mounted therein, uprights secured to the said vent pipe, a fusible member secured to one of the said uprights, a pulley on the other upright, and a chain connected to the said fusible member and passing over the said pulley to connect with the said valve to normally retain the same in open position in the said vent pipe.

3. In a device of the class described, the combination with a vent pipe for connection with a tank, of a valve gravitationally

mounted therein, uprights secured to the said vent pipe, a fusible member secured to one of the said uprights, a pulley on the other upright, a chain connected to the said fusible member and passing over the said pulley to connect with the said valve to normally retain the same in open position in the said vent pipe, and a burner plate

mounted in the said vent pipe over the said valve. 10

In testimony whereof I affix my signature in presence of two witnesses.

JESSE P. MILLER
